UNITED STATES PATENT OFFICE.

THEODORE F. KRUEGER, OF NEW YORK, N. Y.

SINK-TRAP.

SPECIFICATION forming part of Letters Patent No. 625,339, dated May 23, 1899.

Application filed May 24, 1898. Serial No. 681,590. (No model.)

To all whom it may concern:

Be it known that I, THEODORE F. KRUEGER, a citizen of the United States, residing at New York, in the borough of Manhattan and State 5 of New York, have invented certain new and useful Improvements in Sink-Traps, of which the following is a specification.

This invention relates to an improved trap for sinks, washstands, bath-tubs, and other 10 fixtures of a like character by which the automatic sealing of the drain-pipe against the ingress of sewer-gas is produced in an effective and reliable manner and which is opened under hydrostatic pressure when the liquid 15 is to be drained from the sink, washstand, &c.

The invention consists of a sink-trap which comprises a drain-pipe, hinged pipe-sections jointed to said drain-pipe, a receptacle jointed to said pipe-sections, means for counterbalancing the same, and a stop-cock in the lower section of the drain-pipe, operated by the counterbalanced receptacle, so as to be opened for discharge and to be closed after the discharge of liquid.

25 In the accompanying drawings, Figure 1 represents a side elevation of my improved sink-trap shown in closed position; and Fig. 2 is a side elevation, partly in vertical section, showing the parts in position for discharging 30 the liquid from the sink, washstand, &c.

Similar letters of reference indicate corresponding parts.

Referring to the drawings, A represents a sink, washstand, bath-tub, or other fixture, 35 to the under side of which is applied the drain-pipe B. Instead of providing the drain-pipe with the usual S-shaped or other trap, which is objectionable for various reasons, the drain-pipe is made in two parts, one, B', vertically 40 below the other, B, and intermediately between the same is interposed a receptacle C, preferably of cylindrical shape, which is connected at its upper and lower ends by hinged pipe-sections D D' with the sections B B' of the drain-pipe. The weight of the receptacle 45 C and the hinged pipe-sections D D' is counterbalanced by a weighted lever E, which is fulcrumed to the upper section B of the drain-pipe and connected by a chain e with the upper jointed pipe-section D or with the receptacle C, as desired. The weight E' can be

shifted on the arm of the counterbalancing-lever E, so as to produce the proper counterbalancing of the receptacle and hinged pipe-sections D D'.

The hinge-joint between the lower pipe-sections D' and the lower section B' of the drain-pipe is made in the form of a stop-cock f, that turns in a sleeve B², fixed to the upper end of said section B'. The cock f is closed 60 when the receptacle is in the raised position and under the influence of the counterbalancing-weight E', as shown in Fig. 1, or it is opened when the liquid drawn off from the sink, &c., fills the receptacle sufficiently, so 65 as to overcome the counterbalancing-weight E'. When the receptacle C arrives at its lowermost point, as shown in Fig. 2, the fulcrumed lever E abuts against the bottom of the sink A. In this position the stop-cock f 70 is entirely opened, so that the liquid drained off into the receptacle C can easily pass off through the lower section B' of the drain-pipe. As soon as the liquid has flowed off the action of the weight raises the receptacle 75 C and the pipe-sections D D' into upper position, as shown in Fig. 1, in which position the stop-cock f is closed. The closing of the stop-cock f when the trap is in raised or normal position prevents the escape of sewer-gases through the drain-pipe of the same in 80 a very effective and reliable manner. The alternating play of the trap due to the draining off of any of the liquid and to the action of the counterbalancing-weight produces the 85 free draining and the closing of the stop-cock when the liquid has been drawn off.

It is obvious that in place of the counterbalancing-weight a spring may be employed, so as to return the trap into its normal raised 90 position.

Having thus described my invention, what I claim is—

A trap for sinks, washstands, &c., consisting of two fixed sections of drain-pipe, one of 95 which is connected with the sink or basin and the other of which is provided with a fixed sleeve at its upper end, a liquid-receptacle, hinged pipe-sections connecting the said receptacle with the said sections of the drain-pipe, a stop-cock carried and operated by the 100 lower hinged section, said cock turning in

said sleeve and being provided with a passage adapted when the receiver is raised to close the outlet through the lower section of the drain-pipe and when it is lowered to establish communication with the same, and a counterbalancing device for said receptacle, substantially as set forth.

In testimony that I claim the foregoing as my invention I have signed my name in presence of two subscribing witnesses.

THEO. F. KRUEGER.
